CLAIM

The ornamental design for a rear combination lamp for an automobile, as shown and described.

DESCRIPTION

1. Rear combination lamp for an automobile

Reproduction 1.1 is a front perspective view of a rear combination lamp for an automobile showing our new design; reproduction 1.2 is a right front perspective view thereof; reproduction 1.3 is a front elevation view thereof; reproduction 1.4 is a back elevation view thereof; reproduction 1.5 is a right side elevation view thereof; reproduction 1.6 is a left side elevation view thereof; reproduction 1.7 is a top plan view thereof; reproduction 1.8 is a bottom plan view thereof.

The broken lines and the areas within the broken lines in images 1.1, 1.3, 1.4, and 1.6 show portions of the rear combination lamp for an automobile that form no part of the claimed design.

1 Claim, 8 Drawing Sheets
